L. NAHEMOW.
AUTOMATIC ILLUMINATING DEVICE FOR TALKING MACHINES.
APPLICATION FILED DEC. 5, 1917.

1,319,354.

Patented Oct. 21, 1919.

UNITED STATES PATENT OFFICE.

LOUIS NAHEMOW, OF NEW YORK, N. Y.

AUTOMATIC ILLUMINATING DEVICE FOR TALKING-MACHINES.

1,319,354.

Specification of Letters Patent.

Patented Oct. 21, 1919.

Application filed December 5, 1917. Serial No. 205,679.

To all whom it may concern:

Be it known that I, LOUIS NAHEMOW, citizen of the United States, residing at the city of New York, county of Kings, and State of New York, have invented a new and useful Improvement in Automatic Illuminating Devices for Talking-Machines, of which the following is a specification.

This invention relates to devices for the illumination of talking machines near the point of application of the needle to the record, one of the objects being to provide a self-contained electric light device operated automatically by the action of the cover of a talking machine.

Another object of this invention is the provision of a device of this character wherein a standard size and form dry cell battery could be used and its removal or insertion easily effected.

A further object of this invention is to provide an electric illuminating device with novel circuit controlling means operable automatically by the closing and opening of a talking machine cover as well as manually at will. A still further object of this invention is the provision of a portable electric light capable of throwing its rays, approximately, perpendicularly to its base.

With this and other objects in view which will become apparent as the description proceeds, the invention resides in the construction, combination and arrangements of parts as will be hereinafter fully described and claimed and illustrated in the accompanying drawing in which like characters of reference indicate like parts throughout the figures, of which—

Figure 1 is a perspective view of the device,

Fig. 2 is a side elevation,

Fig. 3 is a plan elevation,

Fig. 4 is a section on line 4—4 of Fig. 2,

Fig. 5 is a side elevation showing the lid

raised,

Fig. 6 is a detail view of the key.

The casing 1 is provided at its upper end with a recess 2 and contains a standard size dry cell battery 3 having resilient terminals 4 and 5. The bottom of the casing is provided with extensions 6 having slots 7 to allow an adjustment of the device, which is effected by a lateral movement of the same to or from the side 8 of the cover 9 of the talking machine, thus rendering it adaptable for coöperation with covers varying

in size or form. The casing is secured to the table 10 by screws 11 passing through slots 7 and, in a modified form, may be formed with extensions 6 but bottomless, in which event the table 10 would serve as a bottom for the battery to rest upon. To the top of the casing is hinged at 12 an elongated lid 13 which is formed with a downwardly extending catch 14 adapted to engage the boss 15 of the casing, whereby the lid is held firmly down; and is provided at its free end 16 with integral lugs 17 which are bent upwardly and have perforations 18. The contact arm 19 is formed with integral, bent downwardly lugs 20, and arranged to fit snugly between the lugs 17, which lugs 20 have perforations 21 registering with the perforations 18.

The outer end of the contact arm 19 is provided with notches 22 adapted to hold a soft rubber ring 23, which serves to protect the cover 8 from being scratched by the contact arm when bearing against it, and is bent downwardly to provide a butt 24 for stopping the lid 13 when same is raised for a change of batteries, or to get the lamp out of the way when access to the motor, not shown herein, is desired.

This contact arm is connected pivotally to the end 16 of the lid 13 by a pin 25 which passes through the perforations 18 and 21. On the pin is mounted a spiral spring 26 the end 27 of which bears against the upper side of the end 16, while the other end 28 bears against the under side of the contact arm. To the under side of the lid 13 is riveted a hard rubber plate 29 to which in its turn is riveted a contact member 30 which is insulated from the lid 13 by said plate and is also prevented, by the recess 2 from coming into contact with the walls of the casing, that a short circuit may not occur. The inner end 31 of the contact member is bent upwardly, so as to insure a good contact with the terminal 5, while the outer end 32 is perforated to receive the socket 33 which is soldered or attached in any other suitable way to same and is threaded internally to receive a reflector 34 which in its turn is adapted to receive an electric lamp 35. On the contact arm 19 is mounted loosely a hard rubber key 36 provided with a slot 37, for the manual breaking or making of the electric circuit. In operation, when the cover of the talking machine is raised, the lid 13 being held

down by the catch forms a contact with the terminal 4 of the battery, while the inner end of the contact arm owing to the upward pressure of the spiral spring, is in contact 5 with a pole of the lamp; the end 31 of the contact member is then in contact with the terminal 5 of the battery and the end 32 of the contact member in contact with the other pole of the lamp. As the contact arm is 10 constantly in metallic contact with the lid at the points of their pivotal connection, the circuit is thus completed. Upon lowering the said cover, the side 8 bearing against the rubber ring will depress the outer end 15 of the contact arm and cause thereby the inner end of the same to rise from the pole of the lamp, thus breaking the circuit. When the cover is up and the key 36 is in its normal position, the circuit remains open 20 and may then be closed manually by turning the key to right or left as the inner end of the contact arm would thereby be raised from the pole of the lamp it was in contact with. It is obvious that this device 25 may be attached to any other base or table and used as a manually operable electric lamp without departing from the spirit of my invention.

Having described my invention what 30 I claim as new and desire to secure by Letters Patent is:—

1. An illuminating device of the class described comprising a casing, a battery contained therein, an electric lamp, a contact 35 member connecting a lamp and battery terminal and arranged to hold said lamp downwardly, a key for making and breaking the electric circuit, a rocking contact member connected with the other battery terminal and arranged to contact with the other lamp terminal and to carry said key, and connected to and insulated from the first 40 mentioned contact member.

2. An illuminating device of the class described, comprising a casing, a battery contained therein, an electric lamp, a fixed con- 45

tact member adapted to hold said lamp and arranged to contact with one pole of the battery and with one pole of the electric lamp and a rocking contact member connected to and insulated from said fixed contact member and arranged in electrical contact with the other pole of the battery and to contact with the other pole of the electric lamp and to engage with its other end the 55 cover of a talking machine for the control of the electric circuit.

3. An illuminating device of the character described comprising a casing, a battery, an electric lamp support adapted to contact 60 with a terminal of the battery, a pivotally mounted contact member controlling the lamp circuit and connected to and insulated from said support, an electric lamp attached to said support and projecting downwardly 65 thereof and a key for making and breaking the electric circuit mounted on said contact member.

4. An illuminating device of the character described comprising a casing, a battery, an electric lamp support adapted to contact 70 with a terminal of the battery, a pivotally mounted contact member connected to and insulated from said support and having a downwardly extending end arranged to keep 75 the support and contact members in upright position when changing batteries, an electric lamp attached to said support and projecting downwardly thereof and a key for controlling the circuit mounted on said contact member and arranged to operate between the lamp support and said contact member.

In testimony whereof, I have signed my name to this specification in the presence 85 of two subscribing witnesses, this thirtieth day of November 1917.

LOUIS NAHEMOW.
